Primary Examiner — Ian Simmons*Assistant Examiner* — Charles Hanson(74) *Attorney, Agent, or Firm* — Andrew W. Chu; Craft Chu PLLC(57) **CLAIM**

The ornamental design for the abutment for a dental implant, as shown and described.

DESCRIPTION

FIG. 1 is a perspective view of an abutment for a dental implant showing my new design;

FIG. 2 is a front elevation view thereof;

FIG. 3 is a back elevation view thereof;

FIG. 4 is a side elevation view thereof;

FIG. 5 is an opposite side elevation view thereof;

FIG. 6 is a top plan view thereof; and,

FIG. 7 is a bottom plan view thereof.

The implant portion is shown in broken lines in FIGS. 1-7. The broken lines are for illustrative purposes and form no part of the claimed design.
